UNITED STATES PATENT OFFICE.

SAMUEL SEGAL, OF NEW YORK, N. Y., ASSIGNOR TO SEGAL METAL PRODUCTS COMPANY, INC., OF NEW YORK, N. Y., A CORPORATION OF DELAWARE.

MORTISE LOCK.

Application filed April 7, 1921. Serial No. 459,257.

To all whom it may concern:

Be it known that I, SAMUEL SEGAL, a citizen of the United States, and a resident of New York, in the county of New York and 5 State of New York, have invented certain new and useful Improvements in Mortise Locks, of which the following is a specification.

My invention relates to locks, preferably 10 of the mortise type, and has for its object the production of a lock of strength and simplicity of construction which may be applied to a door or other closure and which shall be adapted to effectively resist efforts 15 against an unauthorized opening of the door by means of jimmying the lock or by force applied in any direction.

A further object of the invention is the 20 production of a lock provided with a spring latch bolt of novel construction and with a locking bolt associated therewith and adapted to move in a plane transverse to the plane of the movement of the latch bolt and to interlock with a suitable keeper.

25 A still further object of the invention is the production of a lock of the character above referred to which shall have suitable means adapted to actuate the locking bolt independently of the latch bolt.

30 Other and further objects and advantages of the invention will appear from the accompanying description, the invention consisting in the novel parts and combinations of the same hereinafter more particularly 35 described and then specified in the claims.

In the accompanying drawings showing a practical embodiment of the invention:

Fig. 1 is a section taken through a door and doorframe with my invention applied thereto showing the rear wall of the lock casing removed and illustrating the position of the parts of the lock when in locked position.

Fig. 2 is a view similar to Fig. 1 but showing the parts in retracted or unlocked position.

Fig. 3 is a vertical cross-section on the line 3—3 of Fig. 1.

Fig. 4 is a horizontal section on the line 4—4 of Fig. 1.

Fig. 5 is a front elevation of the keeper.

Fig. 6 is a horizontal section on the line 6—6 of Fig. 5.

Referring in detail to the drawings:

1 indicates a door which is preferably of 55 the swinging type and 2 indicates the door

frame. A lock casing enclosing the lock mechanism is indicated at 3 and is provided with a front wall 4 and a rear wall or cover 5 which is removable. Said rear wall may be detachably fastened to the casing by 60 means of suitable screws 6 screwed within posts 7 which are secured to the front wall 4. The said casing is preferably mortised in the door 1 intermediate the front and rear 65 faces thereof as shown in Figs. 3 and 4 and it is provided with a removable end wall or plate 8 which is preferably mortised in the door and is flush with the side or edge thereof and which is fastened thereto by suitable screws 9.

10 indicates the cylinder of a conventional pin tumbler lock which cylinder carries the usual escutcheon plate 11 on the forward end thereof engaging the front face or side of the door. The said cylinder extends 75 through a suitable cylindrical opening in the front wall 4 of the casing and it is held in position by means of screws 12 extending through a plate 13 on the rear side of the door, through an opening within the removable cover 5 and threading through ears 14 which are preferably cast as an integral part of cylinder 10. To more effectively hold the cylinder against rotation and in proper position I have provided an elongated screw 15 passing through the end plate 8 of the casing, threading through a suitable support 16 which is secured to the front wall 4 and engaging a groove 17 with which the cylinder 10 is provided. A spindle 18 is connected to the usual key plug (not shown) of the cylinder 10 and it carries an actuating arm or dog 19. Said spindle extends rearwardly through said casing and is operatively connected with the shank of an operating knob 20 which is mounted on the plate 13. As is therefore obvious, the actuating arm or dog 19 may be rotated either by means of a key inserted in the key plug of the cylinder 10 from without the door or by turning the operating knob 20 within the door.

21 indicates a latch bolt which is provided with a groove 22 therein as well as with a transverse slot 23 extending therethrough. Said latch bolt is also provided with a cylindrical opening or bore 24 therein extending through that portion of the latch bolt adjacent the upper side of the slot 23. The said opening 24 communicates with 105 110

the groove 22 and has slidably mounted therein a vertically operating locking bolt 25 movable in a plane transverse to the plane of the movement of the latch bolt and provided with a lower beveled end as illustrated. Said locking bolt 25 is concealed from view by said latch bolt when in normal or unlocked position and is supported thereby. When thrown into locked position 10 said locking bolt 25 moves across or spans the slot 23 and enters a bore 26 in the latch bolt 21 adjacent the lower side of said slot and in alignment with said cylindrical opening 24 (see Fig. 1) whereby either end of 15 the locking bolt is supported by the latch bolt within the bores 24 and 26 respectively.

Extending within the lock casing is a shank 27 provided with a slot 28 therein within which is pivoted, as at 29, a locking 20 bolt actuating lever 30 provided with a slot 31. The forward end of said actuating lever 30 enters the groove 22 in the latch bolt 21 and it is provided with an opening 32 receiving a ball 33 secured to the locking bolt 25 by an arm 34 extending through the communicating slot in the latch bolt intermediate the opening 24 and groove 22. The connection between the actuating lever 30 and locking bolt 25 is thus the well known 30 ball and socket connection as has been described. The rear end of the shank 27 of the latch bolt is provided with a flange or reinforcing member 35 adapted to abut against a side wall of the lock casing when 35 said latch bolt is in retracted position, said side wall acting as a stop to limit the movement of the latch bolt within the casing. Said shank is also provided with an opening 36 extending therethrough and with a 40 squared indentation 37 in the upper side thereof. The said shank slidably rests on a support 38 secured to the front wall 4 of the casing and it is guided in its movement within said casing by guides 39 and 40 fastened to the front wall 4 and rear wall 5 respectively. The said support 38 is also adapted to engage the flange 35 of the shank 27 and it acts as a stop to limit the forward movement of the latch bolt in the 50 casing.

The lower end of the latch bolt 34 is provided with an elongated portion 41 constituting the base of said latch bolt and which is provided with outer beveled or inclined edges 42 as illustrated. The latch bolt is supported within a slot 43 in the end wall or plate 8 of the casing, said slot being elongated at its lower end and of a configuration and size permitting it to receive 60 the base 41. The front wall 4 and rear wall or cover 5 of the casing are provided with housings 44 and 45 respectively open on their inner sides and registering with the elongated portion of the slot 43, said housings being adapted to receive and support

the ends of base 41 of the latch bolt and to guide said latch bolt in its movement within the lock casing.

46 indicates a plate pivotally mounted on a pin 47 extending transversely through the lock casing and supported by the front and rear walls thereof. Said plate is provided with a pin 48 extending through the slot 51 of the lever 30 and said plate is supported by a rib 49 secured to the front wall 4 of the lock casing. 50, 50' indicate lugs on said plate 46 having outer inclined curved or beveled surfaces and 51 is a slot in said plate intermediate said lugs. A tumbler pawl is indicated at 52 and is pivoted as at 53 to said plate 46. Said tumbler pawl is provided with an inwardly projecting arm 54 extending within the slot 51 and provided with a reduced end 55 adapted to engage a post or lug 56 on the front wall 4 of the casing. A spring 57 is carried by the pivot 53 and one end thereof engages a pin 58 on said tumbler pawl while the other end engages a pin 59 on the plate 46. The action of said spring 57 tends to swing the plate 46 on its pivot 47 in a counter-clockwise direction and also the tumbler pawl 52 on its pivot 53, in a like direction. The plate 46 is provided with a shoulder 60 adapted to engage the squared indentation 59 on the shank 27 of the latch bolt.

61 indicates a door knob mounted on the outside of the door while 62 indicates a door knob mounted on the inside of the door. Said door knobs are provided with a single or common shank 63 extending through a hub 64 within the lock casing which hub is provided with wings or arms 65 rotatable therewith and adapted to engage lugs 66 on the legs of a forked member 67. Said forked member is provided with a pin 68 and the ends of the arms of said member are adapted to engage posts 69 fastened to the end wall of the lock casing, which posts act as stops to limit the movement of the forked member and which also act as rests or supports for the cover plate 5.

70 indicates a lever pivoted as at 71 to the front wall 4 of the lock casing. Said lever is provided with an upper knobbed end 72 entering the opening 36 in the shank of the latch bolt and with a slot 73 receiving the pin 68 of the forked member 67. 74 indicate springs carried by the pivot 71, the lower ends of said springs engaging the base of the casing. The upper end of one of said springs engages a pin 75 on the lever 70 while the upper end of the other of said springs engages the pin 68. The action of one of said springs, to wit: the spring that engages the pin 75, tends to rotate the lever 70 on its pivot 71 in a counter-clockwise direction to throw or project the latch bolt forwardly through the slot 43 in the end wall 8 of the casing in an obvious manner,

while the action of the other of said springs tends to force the forked member 67 to the left and to maintain contact between the wings 65 and the lugs 66 of the forked member.

76 indicates the rear wall, 77 the side walls and 78 the front wall or plate of a keeper housing which is mortised in the door casing 2 and which is screwed thereto by screws 79 passing through the rear wall and front wall of said housing as indicated in Fig. 1. The front wall 78 of said keeper housing is provided with an I-shaped slot the horizontal portions 80' of which are of a size and configuration adapting them to receive the base 41 of the latch bolt while the vertical portion of said slot is adapted to receive the main or body portion of said latch bolt. The front wall 78 is provided with a striker plate 81 adapted to be engaged by the latch bolt as will be herein-after described. The said slot 80 is of the configuration described and illustrated so as to permit the position of the housing to be reversed from that shown, the position in which it is mounted depending on whether the door to which the lock is applied is swung inwardly or outwardly, it being desirable to have the housing so positioned that the striker plate thereof will first contact with the latch bolt when the door is swung closed. As is obvious, the slot 80 and one of the horizontal portions 80' thereof will always receive the latch bolt and its base respectively regardless of whether the keeper housing is mounted in the position shown or whether it is mounted in reverse position, that is, turned through an angle of 180° and then mounted.

10 The rear wall of the keeper housing is provided with an annular opening 82 receiving a cylindrical rod 83 having a flange 84 at its rear end. Said rod is of a size somewhat smaller than that of the opening 82 to permit a slight movement of said rod in said opening in any direction. A keeper plate or ear is indicated at 85 and said plate is preferably integral with said rod 83. Said plate is provided with shoulders 86 adapted to engage the rear wall of the keeper housing, the rod 83 being of a length to permit a slight forward and rearward movement of said plate 85 which movement is limited by the flange 84 and shoulders 86 striking or abutting against the rear wall 76 of the keeper housing. 87 indicates a cylindrical opening extending through said plate, the plate being beveled adjacent the edge of said opening as indicated at 88 and at its outer edges as indicated at 89. When the latch bolt enters the slot 80 the plate 85 is received by the slot 23 in said latch bolt with the opening 87 in the plate in vertical alignment with the opening 24 and bore 26 in the latch bolt. When the locking

bolt 25 is thrown into locked position it extends through the opening 87 in said plate and into said bore 26 and accordingly securely interlocks with said plate.

15 In the event of the lock casing or keeper housing being thrown out of alignment with each other due to the warping or sagging of the door or door frame or because of other reasons, the keeper plate 85 will nevertheless enter the slot 23 as one of the beveled edges 89 thereof will strike against an edge of the latch bolt adjacent said slot thus forcing the plate within the slot. Furthermore, the locking bolt 25 will always enter the opening 87 in the keeper plate for the reason that if the plate is out of proper alignment the lower beveled end of the locking bolt will strike against the beveled edge 88 adjacent said opening 87 to automatically properly position said plate as said plate is capable of slight movement in any direction as has been herein-before described.

20 The latch bolt normally extends through the slot 43 in the end plate due to the action of one of the springs 74, but it may be drawn within the casing if the locking bolt is in raised or unlocked position by turning either of the handles 61 or 62 in either direction. This action rotates the hub 64 which carries the wings or arms 65 with it thereby forcing one of said wings to press against one of the lugs 66 to force the forked member 67 from the position shown in Fig. 1 to that shown in Fig. 2. Due to the pin and slot connection between the forked member 67 and the lever 70, said lever is rocked on its pivot 71 in a clockwise direction and the knobbed end 72 of said lever draws or retracts the latch bolt within the casing against the action of said spring 74. As soon as the handle is released the latch bolt is immediately again thrown forwardly through the slot 43 by the action of the spring 74, said forward movement being limited by the engagement of the flange 35 with the support 38. When the door is swung into closed position it becomes automatically latched for the reason that the latch bolt strikes against or engages the striker plate 81 to force the latch bolt within the lock casing which is accomplished without affecting the position of the forked member 67. When the door, however, reaches its extreme closed position the latch bolt is automatically projected, by the action of the spring 74, through the slot 80 of the keeper housing to hold the door in closed position until either of the handles 61 or 62 has been rotated and the door pushed open in the manner previously described.

25 The vertically operating locking bolt 25 may be actuated to cause the same to interlock with the keeper plate as has been explained either by turning the operating

- knob 20 or by means of a key inserted in the key plug of the cylinder whereby a rotation of the actuating arm or dog 19 is effected. When the locking bolt is in projected or locked position it is that position shown in Fig. 1 and it is held in locked position by engagement of the reduced end 55 of the arm with the left-hand side of the post or lug 56 which prevents the plate 46 from being rocked on its pivot 47. If the latch bolt is also in projected position the shoulder 60 of the tumbler pawl 52 engages the indentation 37 on the shank 27 of the latch bolt which prevents said latch bolt 15 from being drawn inwardly within the casting by a turning of the handles 61 or 62.
- To retract said locking bolt or draw it upwardly into unlocked position the actuating arm or dog 19 is rotated in a counter-clockwise direction to cause the end thereof to engage and press against the arm 54 and cause the tumbler pawl 52 to swing downwardly on its pivot 53 against the action of the spring 57. Further movement of the 20 arm 19 causes the end thereof to engage and press against the lugs 50' on the plate 46 which rocks said plate on its pivot 47 in a clockwise direction thereby rocking the actuating lever 30 on its pivot 29 due to the pin 25 and slot connection between said plate and actuating lever. The movements just described raise the locking bolt in an obvious manner and after the arm or dog 19 has cleared the arm 54 the tumbler pawl swings 30 upwardly on its pivot by the action of spring 57 and the reduced end 55 of the arm 54 engages the post 56 on the right-hand side thereof, thereby preventing the plate 46 from swinging on its pivot and holding the locking bolt in raised and unlocked 35 position. (See Fig. 2.)
- To throw the locking bolt downwardly into locked position the actuating arm or dog 19 is rotated in a clockwise direction. 40 The end thereof first engages the arm 54 of tumbler pawl 52 pressing said arm downwardly to release the reduced end 55 thereof from engagement with the right-hand side of post 56. Further movement of said arm 45 or dog causes the same to press against the lug 50 on plate 46 and said plate is swung in a counter-clockwise direction on its pivot 47 to throw the locking bolt into locked position in an obvious manner. The spring 57 50 swings the tumbler pawl 52 upwardly on its pivot and the reduced end of the arm 54 again engages the left-hand side of the post 56 to hold the locking bolt in locked 55 position. It will be manifest from the foregoing description that the locking bolt may be actuated independently of the latch bolt and irrespective of the position of said latch bolt.
- What I claim as my invention is:
- 60 1. In a door lock, a keeper, a latch bolt

mounted on the door and provided with a slot and an opening therein and adapted to enter said keeper and a locking bolt mounted in said opening and extending across said slot when in locked position. 70

2. In a door lock, a keeper, a latch bolt mounted on the door and provided with a slot and a bore therein and adapted to enter said keeper and a locking bolt slidably mounted within said bore, said locking bolt 75 being concealed by said latch bolt when in unlocked position and extending across said slot with both ends supported within said bore when in locked position.

3. In a door lock, a keeper, a latch-bolt 80 mounted on the door and adapted to enter said keeper, a locking bolt carried by said latch-bolt and means associated with said keeper for interlocking with said locking bolt and provided with an opening adapted 85 to receive said locking bolt therein.

4. In a door lock, a keeper, a latch-bolt mounted on the door and having a slot therein and adapted to enter said keeper, a locking bolt carried by said latch-bolt and 90 movable in a plane transverse to the direction of movement of said latch-bolt and means associated with said keeper and adapted to enter said slot and to receive said locking bolt for interlocking therewith. 95

5. In a door lock, a keeper, a latch-bolt mounted on the door and adapted to enter said keeper, a locking bolt carried by said latch bolt and adapted to interlock with 100 said keeper, means for actuating said locking bolt independently of said latch bolt and means engaging said locking bolt and adapted to interlock with said latch bolt for preventing movement of said latch bolt when said locking bolt is in locked position. 105

6. In a door lock, a keeper, a latch bolt mounted on the door and adapted to enter said keeper, means for actuating said latch bolt, a locking bolt carried by said latch bolt, means connected to said latch bolt for actuating said locking bolt and means forming a part of said lock and adapted to engage said latch bolt to prevent actuation thereof by said latch bolt actuating means. 110

7. In a door lock, a keeper, a latch bolt mounted on the door and provided with a slot therein and adapted to enter said keeper, a plate associated with said keeper and adapted to enter said bolt and a locking bolt adapted to interlock with said plate. 115

8. A lock, including, in combination, a keeper, a bolt comprising a pair of parts movable one to each side of said keeper, means carried by said bolt and extensible through an opening in said keeper, and operating means for said bolt and said last-named means. 120

9. A lock, including, in combination, a keeper, a bolt comprising a pair of parts movable one to each side of said keeper, 130

means carried by one of said bolt parts and extensible through an opening in said keeper to a point adjacent the other of said parts for preventing a retraction of said bolt, and operating means for said bolt and said last-named means.

10. In a door lock, a keeper housing, a spring latch bolt mounted on the door and adapted to be automatically projected in said keeper housing when the door is closed, a locking bolt carried by said latch bolt, means within said keeper housing for interlocking with said locking bolt, means for actuating said locking bolt independently of said latch bolt and means engaging said locking bolt and adapted to interlock with said latch bolt for preventing movement of said latch bolt when said locking bolt is in locked position.

20. 11. In a door lock, a keeper, a movable plate supported by a wall thereof and provided with an opening therein, a locking bolt movable towards and away from said keeper, and means having a beveled end mounted on the door and adapted to extend through the opening in said plate.

20. 12. In a door lock, a keeper, a movable plate extending through an opening in a wall thereof and provided with an opening therein and with means adapted to engage said wall to limit the movement of said plate, a bolt movable towards and away from said keeper, and means carried by said bolt and movable transversely of the direction of movement of the same and adapted to extend through the opening in said plate.

20. 13. A lock, including, in combination, a keeper, a movable plate forming a part thereof and provided with an opening, a bolt, and means for projecting and retracting said bolt through said plate opening, said plate being movable in a direction to either side of said bolt.

20. 14. In a door lock, a keeper, a latch bolt mounted on the door and adapted to enter said keeper, a locking bolt carried by said latch bolt and normally concealed thereby and a plate within said keeper having an opening for receiving said locking bolt.

20. 15. In a door lock, a keeper, a latch bolt mounted on the door and provided with a slot therein and a locking bolt slidably mounted within said latch bolt, said locking bolt extending across said slot when in locked position with both ends thereof concealed and supported by said latch bolt.

20. 16. In a door lock, a keeper, a latch bolt mounted on the door and having a slot therein, said latch bolt being adapted to extend within said keeper, means within said keeper adapted to extend within said slot and a locking bolt carried by said latch bolt and adapted to extend across said slot and to interlock with said means within said keeper.

17. In a door lock, a keeper, a movable latch bolt mounted on the door and adapted to be automatically projected within said keeper when the door is closed, said latch bolt having a slot extending transversely therethrough, means within said keeper adapted to extend within said slot and a locking bolt carried by said latch bolt and movable in a plane transverse to the direction of movement of said latch bolt and adapted to extend across said slot and through said means within said keeper and to interlock therewith.

18. In a door lock, a keeper, a movable latch bolt provided with a base having inclined sides, said latch bolt being adapted to be projected within said keeper when the door is closed upon engagement of said inclined sides with said keeper and a locking bolt carried by said latch bolt and adapted to interlock with said keeper.

19. In a door lock, a keeper, a movable latch bolt adapted to enter said keeper and provided with a slot extending transversely therethrough and with an opening therein, means within said keeper adapted to extend within said slot and a locking bolt slidably mounted within said opening and adapted to move across said slot and through the means in said keeper and to interlock therewith.

20. In a door lock, a keeper, a lock casing mounted on said door and provided with a slot therein, a movable latch bolt including a body adapted to enter said keeper and extensible through said slot and a locking bolt carried by said latch bolt and movable within the space defined by its body, said locking bolt being adapted to interlock with said keeper.

21. In a door lock, a keeper, a lock casing mounted on said door and provided with a slot therein, a latch bolt slidably mounted in said casing and extensible through said slot and adapted to enter said keeper and a locking bolt including a body carried by said latch bolt and movable within the space defined by said body and in a plane transverse to the direction of movement of said latch bolt, said locking bolt being adapted to interlock with said keeper.

22. In a door lock, a keeper, a lock casing mounted on said door and provided with a slot therein, a latch bolt provided with a slot extending transversely therethrough, said latch bolt being slidably mounted in said casing and normally extending through the slot in said casing, means carried by said keeper adapted to enter the slot in said latch bolt and a locking bolt carried by said latch bolt and adapted to move across the slot in the latch bolt and to extend through the means in said keeper and to interlock therewith.

23. In a door lock, a keeper, a lock casing

- 6 mounted on said door and provided with a slot therein, a latch bolt movable through said slot and adapted to enter said keeper, a locking bolt carried by said latch bolt and 5 adapted to interlock with said keeper, a plate pivotally mounted in said casing, a lever pivoted to said latch bolt and connected to said locking bolt and said plate, a tumbler pawl pivotally mounted on said 10 plate, means in said casing engaging said tumbler pawl to retain said locking bolt in projected or retracted position, an actuating arm for releasing said tumbler pawl from engagement with said means and for 15 rocking said plate on its pivot to actuate said locking bolt and means operable from within or without the door for actuating said latch bolt.
24. In a door lock, a keeper, a lock casing 20 mounted on said door and provided with a slot therein, a latch bolt slidably mounted in said casing and movable through said slot and adapted to enter said keeper, a locking bolt carried by said latch bolt and adapted 25 to interlock with said keeper, a plate pivotally mounted in said casing and provided with means adapted to engage said latch bolt to prevent movement thereof, a locking bolt lever pivoted to said latch bolt and connected 30 to said locking bolt and said plate, a tumbler pawl pivotally mounted on said plate, a lug on said casing engaging said tumbler pawl to retain said locking bolt in projected or retracted position, means acting 35 to retain said tumbler pawl in engagement with said lug, an actuating arm for releasing said tumbler pawl from said engagement and for rocking said plate on its pivot to actuate said locking bolt, a lever pivotally 40 mounted in said casing and engaging said latch bolt, means engaging said lever and acting to retain said latch bolt in projected position through said slot and means connected with said lever for rocking the 45 same on its pivot to actuate said latch bolt and operable from within or without the door.
25. A lock including in combination a bolt, means for moving said bolt, a bar carried by said bolt and adapted for movement in a direction substantially transverse to the direction of movement of said bolt, unitary means for moving said bolt-moving means and said bar, and an apertured keeper having a seat for the reception of said bolt and another seat for the reception of said bar, said bolt and bar interlocking within said keeper.
26. A lock including in combination two 50 movable members one carried by the other and adapted for movement in substantially transverse directions respectively, one of said movable members being provided with a seat for the reception of the other of said 55 movable members, means for moving one of said members into position to be engaged by the other member, and a keeper having two transversely disposed seats, one adapted for the reception of one of said movable members and the other for the reception of the other movable member.
27. A lock, including a keeper formed with an opening, a bolt formed with a slot, means for projecting said bolt to cause said keeper to enter said slot, and means carried 60 by said bolt and extensible through an opening in said keeper to normally prevent a retraction of the former.
28. In a lock structure, the combination with a lock casing and a keeper, of a main bolt structure including a plurality of members to enter the keeper, a vertically movable auxiliary bolt structure carried by the main bolt structure and including a member to project from one of said main bolt members and adapted to interlock with an adjacent main bolt member and with the keeper.
29. A lock, including a keeper formed with an opening, a bolt formed with a slot, means for projecting said bolt to cause said 70 keeper to enter said slot, means carried by said bolt and in one position to one side of said slot, said means being projectible across said slot and through an opening in said keeper to prevent a retraction of said bolt.
30. A lock, including a keeper formed with an opening, a bolt formed with a slot, means for projecting said bolt to cause said keeper to enter said slot, means carried by said bolt and in one position to one side of 75 said slot, said means being projectible across said slot and through an opening in said keeper and into a recess formed in the slot face of said bolt to prevent a retraction of the latter.
31. A lock, including, in combination, two movable members adapted for movement in substantially transverse directions respectively, one of said movable members being adapted to engage with the other of the 80 same, and means forming a part of the lock for simultaneously moving both of said members while retaining the same against movement with respect to each other, and thereafter moving said members into engagement.
32. A lock, including, in combination, a bolt and a bar, said bar being adapted to be engaged by said bolt, means for moving said bar and bolt in unison while maintaining 85 the same against movement with respect to each other, and thereafter moving said bar and bolt relatively to and into engagement with each other, and an apertured keeper having seats for the reception of said bolt 90 and bar.
33. A lock, including, in combination, a pair of members movable transversely of

and into engagement with each other, means for moving both of said members while maintaining the same against movement with respect to each other, and means for thereafter moving said members relatively to and into engagement with each other, and a keeper having two transversely-disposed

seats, one adapted to receive each of said members.

Signed at New York in the county of 10
New York and State of New York this 6th
day of April, A. D. 1921.

SAMUEL SEGAL.
